UNITED STATES PATENT OFFICE

109,029

DESIGN FOR A LAMP

Jacob S. Sherman, Chicago, Ill.

Application January 26, 1938, Serial No. 74,535

Term of patent 14 years

To all whom it may concern:

Be it known that I, Jacob S. Sherman, a citizen of the United States and resident of Chicago, in the county of Cook and State of Illinois, have invented a new, original, and ornamental Design for a Lamp, of which the following is a specification, reference being had to the accompanying drawing, forming a part thereof.

Fig. 1 is an elevational view of a lamp showing my new design.

Fig. 2 is a top plan view of the same.

Fig. 3 is a sectional view taken substantially on the line 3—3 of Fig. 1.

I claim:

The ornamental design for a lamp substantially as shown.

JACOB S. SHERMAN.
